UNITED STATES PATENT OFFICE

95,489

DESIGN FOR A TEXTILE FABRIC OR SIMILAR ARTICLE OF MANUFACTURE

Gertrude Deist, New York, N. Y.

Application January 10, 1935, Serial No. 54,790

Term of patent 3½ years

To all whom it may concern:

Be it known that I, Gertrude Deist, a citizen of the United States, and a resident of the Borough of Manhattan, city, county, and State of New York, have invented a new, original, and ornamental Design for Textile Fabric or Similar Article of Manufacture, of which the following is a specification, reference being had to the accompanying drawing forming a part thereof.

The figure of the drawing is a plan view of a piece of textile fabric showing the unit constituting my design.

I claim:

The ornamental design for a textile fabric or similar article of manufacture, as shown and described.

GERTRUDE DEIST.
